ATTORNEY.

UNITED STATES PATENT OFFICE.

DAVID CARSWELL, OF ST. JOSEPH, MISSOURI.

FLY-KILLER.

1,655,123.

Specification of Letters Patent.

Patented Mar. 4, 1913.

Application filed August 23, 1912. Serial No. 716,611.

To all whom it may concern:

Be it known that I, DAVID CARSWELL, a citizen of the United States of America, residing at St. Joseph, in the county of Buchanan and State of Missouri, have invented certain new and useful Improvements in Fly-Killers, of which the following is a specification.

The object sought by me in this invention is to provide a device for destroying flies and other insects which combines simplicity of construction, durability, low cost and adaptability to the purpose for which made.

I accomplish my object by the mechanism illustrated in the accompanying drawings in which,

Figure 1 is a front view of the device showing a flap with folded corners and side edges, a supporting handle, diverging arms within said folded corners and tubular rivets two of which are in engagement with the hooked ends of the diverging arms; Fig. 2 is a detail of one of said tubular rivets, and Fig. 3 is one of said folded corners of the flap inclosing one of said arms the tubular end of a rivet inserted through the flap and through the hook on the end of one of the arms, the tubular end of the rivet spread and crushed on the hook and the corner of the flap.

Similar letters refer to similar parts throughout the several views, A being the body of a flap made of wire cloth and B is a supporting handle therefor. Said handle is preferably made of a single strand of wire its lower end looped, the body thereof twisted upon itself as shown in Fig. 1, the inner ends of the strand forming diverging arms C C, the tip ends of the strand reversed forming hooks D D, as shown in Figs. 1 and 3. The outer or top edge A' of said flap A is selvaged to prevent fraying and the sides A² A² of the flap are bent backward and folded against the body of the flap thereby stiffening the same. Corners E E of the flap are likewise folded backwardlapping each other as shown in Fig. 1 forming a V shape inclosure for said arms C C and hooks D D. F is a tubular rivet as shown in Fig. 2. In constructing the device preferably three of these rivets are used.

Ordinarily I insert the rivets by means of a riveting machine which drives them through the mesh of the flap simultaneously splitting or spreading the tubular parts f f and mashing them on said folded corners E E, thereby engaging hooks D D in rigid position within said folds, while the third or central rivet engages with corners E E passing through the wire cloth where the corners lap each other and also through the folded edges of both sides A² A², thus holding between the rivet head and the crushed tubular end thereof five thicknesses of wire cloth. By the construction shown and described the connection of the flap with the handle is rendered firm and durable while the flap end retains all needed flexibility.

What I claim and desire to secure by Letters Patent is,—

1. A device for destroying flies and other insects comprising a wire screen cloth flap, a wire selvage along the top edge thereof, the side edges of the flap folded their entire length thereby stiffening the same, the bottom corners of the flap folded backward the edges thereoflapping each other forming a central stiffening, a handle constructed of a single strand of stiff wire looped at the middle, twisted rigidly upon itself from the loop to the flap, the diverging arms and hooks formed by the ends of said strand, riveted through said flap and folded corners, engaging with said hooks also riveted through the lapped edges and body and folds of said flap each rivet crushed upon the back of the device.

2. In a wire cloth flap having folded edges and a handle with diverging ends held within the folded corners of said flap and tubular rivets therefor, of inwardly hooked top ends of said handle to permit the folded corners of said flap and said tip ends to be riveted together and a midway rivet inserted through the five ply thickness of wire.

In testimony whereof I affix my signature in presence of two witnesses.

DAVID CARSWELL.
